WILLIAM H. VAN GIESON, OF PASSAIC, NEW JERSEY.

Letters Patent No. 61,485; dated January 22, 1867.

IMPROVED CORK-SCREW.

The Schedule referred to in these Letters Patent and making part of the same.

Specification of certain improvements in Cork-Screws, invented by WILLIAM H. VAN GIESON, of Passaic, in the county of Passaic, and State of New Jersey.

The object of my invention is to produce a cork-screw which shall be rapid and simple in its operation, as well as strong and durable, and not too bulky to be convenient in handling.

To accomplish this object, I attach to the middle of the handle a metallic tube, in the position usually occupied by the shank of the instrument, and extend the shank of the screw or spiral to about double its usual length, making the upper part in the form of a regularly twisted square, or other prism-shaped rod, having about one twist to the inch, and turned in the opposite direction from that of the screw or spiral itself, and make this twisted square portion to run up into the said tube through a plate at its lower extremity. This plate has a hole through it, of the exact form of the twisted rod, acting on the rod in the manner of a screw-nut, so that as the rod passes up into the tube, it is caused to revolve on its axis, thus driving the screw or spiral into the cork against which it is pressed. When the twisted square rod is thus driven up into the tube, and the screw or spiral into the cork, a spring-catch, which is fastened to the lower end of the tube, catches under a shoulder at the lower end of the square rod, where it joins the shank of the spiral, and holds it securely while the cork is being withdrawn. The cork can be removed in the usual way, or the spring-catch may be disengaged, and the twisted part drawn out, ready for use again. In the last case the cork would be run off from the spiral at the same time. In the accompanying drawings—

Figure 1 is a side elevation of my improved cork-screw, with the twisted part within the tube.

Figure 2 is a side elevation of the same, with the stem drawn out.

Figure 3 is a cross-section, through $z z$, fig. 1, showing the spring-catch thrown out.

Figure 4 is a similar section, with the spring-catch locked under the shoulder on the shank or stem.

Figure 5 is a cross-section, through the line $x x$, fig. 1.

Figure 6 is a cross-section, through the line $y y$, fig. 2.

The shank or stem of the cork-screw consists of two parts, the spiral or screw part, A, which enters the cork for the purpose of pulling it, and which is or may be constructed in the usual manner, and the twisted portion B, which is simply a square or other prism-shaped rod, twisted in the direction the reverse of that of the spiral or screw A. At the junction of these two parts there is a shoulder, C. At the upper end of the part B there is a head or button, D, (shown in dotted lines,) which prevents the said part B from coming entirely out of the tube. E is the tube and F the handle. The tube E is secured in the handle F by the rivet or pin G. At the lower extremity of the tube E, the twisted rod B passes through an opening in the plate H, figs. 5 and 6, which is securely fastened to the tube E, the said opening being of the form of a section of the said twisted rod, so that when the rod is forced through the said opening, either into or out of the tube, it is caused to revolve, thus operating the spiral or screw A. The pitch of the twist of the part B is very steep, so that it may be forced through the opening in the plate H with comparative ease, that exhibited in the drawings being intended to represent about one full turn to the inch. I is a spring-catch, which is held up against the stem by the circular spring J, and which is set into a slot in the end of the tube, so as to give it great strength to resist the effects of the force applied to the cork-screw in using it. It is pivoted on a pin, a, in the end of the tube E, and has an additional pin, b, inserted in it, which prevents the spring-catch from being thrown out too far by striking against the end of the slot c.

In using my cork-screw, the stem is first thrown out, which can easily be done by pressing back the spring-catch I, and the point of the spiral or screw A being placed against the centre of the cork, the handle is forced down, thereby turning the twisted part B and spiral A, and forcing the said spiral into the cork. So soon as the shoulder C passes above the spring-catch I, the said spring-catch hooks under the said shoulder, and gives a bearing against which the stem is supported while the cork is being pulled. The cork may be easily drawn from the cork-screw by throwing the spring-catch I out and pulling it off, the stem meanwhile running out. With this instrument it takes but an instant to draw a cork, while the cork-screw itself is simple, durable, and easily manipulated.

Having thus fully described my invention, I claim—

1. Constructing the upper part B of the stem in the form of a twist, spiral, or screw, turned in a direction the reverse of that of the lower part A, substantially as and for the purpose set forth.
2. The combination with the stem A B, constructed substantially as described, of the tube E, plate H, or its equivalent, spring-catch I, and handle F, the whole working together in the manner and to accomplish the result set forth.

W. H. VAN GIESON.
